DESIGN FOR A COMBINATION TOP AND ARTICLE HOLDER FOR TOILET TANKS

Frank W. Brown, Jr., Richmond, Va.

Application December 22, 1936, Serial No. 66,689

Term of patent 7 years

To all whom it may concern:

Be it known that I, Frank W. Brown, Jr., a citizen of the United States, residing at Richmond, county of Henrico, State of Virginia, and whose post office address is #4307 Cutshaw Avenue, in said city, have invented a new, original, and ornamental Design for a Combination Top and Article Holder for Toilet Tanks, of which the following is a specification, reference being had to the accompanying drawing constituting a part thereof.

In the drawing:—

Fig. 1 is a front perspective view of a combination top and article holder for toilet tanks showing my new design.

Fig. 2 is a top plan view thereof.

I claim:

The ornamental design for a combination top and article holder for toilet tanks, substantially as shown.
